DESOLDERING TOOL

Alvis R. Knowles, Torrance, Calif., assignor to Eldon Industries, Inc., Hawthorne, Calif., a corporation of California

Filed Oct. 9, 1968, Ser. No. 13,893

Term of patent 14 years

Int. Cl. D8—02

U.S. Cl. D8—30

FIG. 1

FIG. 2

FIG. 3

FIG. 4

FIG. 1 is a side elevational view of a desoldering tool embodying the design of my invention;

FIG. 2 is a front elevational view thereof;

FIG. 3 is a top elevational view thereof;

FIG. 4 is a bottom elevational view thereof.

I claim:

The ornamental design for a desoldering tool, substantially as shown and described.
